UNITED STATES PATENT OFFICE.

OSCAR ROESEN AND ISIDOR TORNBERG, OF NEW YORK, N. Y., ASSIGNEES TO R. HOE AND CO., OF NEW YORK, N. Y., A CORPORATION OF NEW YORK.

PLATE-CLAMP-OPERATING TOOL.

1,414,485.

Specification of Letters Patent.

Patented May 2, 1922.

Original application filed November 10, 1915, Serial No. 60,652. Divided and this application filed February 11, 1918. Serial No. 216,473.

To all whom it may concern:

Be it known that we, OSCAR ROESEN and ISIDOR TORNBERG, citizens of the United States, residing at New York city, county 5 of Kings, State of New York, have invented certain new and useful Improvements in Plate - Clamp - Operating Tools, fully described and represented in the following specification, and the accompanying drawings, forming a part of the same.

This invention relates to certain improvements in tools for operating plate clamps, and the tool has been particularly designed for operating the clamp shown and described 15 in our joint application Serial No. 60652, filed November 10, 1915, of which application the present application is a division, the subject-matter whereof was divided out of the original application by Patent Office 20 requirement.

The especial object of the present invention is to provide an improved tool which can be readily positioned in relation to the clamp, and firmly and securely locked in 25 such position so that the clamp may be adjusted readily and accurately with relation to the plates. While the tool of the present application may be used in other relations and with other types of clamps, it has been 30 designed particularly for use with the clamp shown and described in our application above referred to, to which reference may be had for a full understanding of the construction. To enable the use of this tool 35 with such clamp to be fully understood, such clamp will be briefly described in this application in connection with the accompanying drawings, which show the clamp and the tool in operative relation therewith. In 40 these drawings—

Figure 1 is a side elevation of the improved tool;

Figure 2 is an end elevation, partly in section, with certain parts broken away, 45 showing the tool in operative relation with the clamp;

Figure 3 is a cross sectional view, partly broken away, of the clamp and the operative part of the tool shown in operative relation 50 with the clamp, and

Figure 4 is a detail sectional view taken on the line 4—4 of Fig. 2.

Referring now to these drawings, the clamp includes an adjustable member 1,

which may be locked in a groove or slot 2 in a plate support. Cooperating with this member 1, which may be termed an anchor base, is a clamp carrier made in the form of a screw having a threaded shank 3 and a two-part head 4, 5 connected by a web 6. This carrier is anchored to the base by positioning the head 4 of the screw and the web 6 in a slot 7 formed in one end of the base 1, the screw being prevented from turning by flattening one of the heads as shown at 8. The plate clamp, marked 9, is movable on the carrier so as to position the clamp in proper relation to the plate for adjusting the plate relatively to the bed, which movement is effected by the tool hereinafter described. While this may be effected in various ways, a clamp moving device is provided consisting of a nut 10 on the threaded shank 3, before referred to. This nut is provided with a flange 11 which takes into a groove 12 in the clamp, thus causing the clamp to move with the nut. This nut is a gear nut having a gear or wheel 13. When the gear is turned the clamp mover is advanced or dragged along the shank of the carrier and the plate consequently locked or unlocked from clamping position or moved for adjustment.

For operating this and similar clamps, there is provided by the present invention an improved tool, the specific construction of which may vary. In the best embodiments of the tool, however, it will be provided with means for cooperating with the clamp, whereby the tool is held in rigid locked relation with the clamp during the clamp-adjusting or moving operation. In the best embodiments of the tool, furthermore, the operative parts of the tool will be enclosed in a head or casing, so that the operator will be protected from the moving parts and the moving parts of the tool will be protected from dust or dirt, or other foreign substances which, getting into the operative parts, might injure them.

A tool embodying these features is illustrated and, as shown, includes a head or casing 14 and an operating handle 15 having a milled or otherwise roughened end 16 to afford a firm grasp by the operator in manipulating the tool. The tool includes gearing, by the rotation of which the gear nut 10 is rotated to effect the movement of

the clamp. In the best constructions, to permit the moving parts to be assembled in as small space as possible, thus permitting a small, handy tool, miter gears may be 5 employed and the handle will be vertically arranged with respect to the tool. While the specific arrangement of these gears may be somewhat varied, in the particular construction shown there is a vertical operating 10 shaft 17 suitably fixed to the operating handle 15, as by a set screw 18 passing through the wall of the handle and taking into a groove 19 in the shaft. The shaft 17 passes through a head 20 of the casing 15 and takes bearing in the lower wall 21 of the head, this wall being preferably a sloping one, as shown in Fig. 3, to enable the tool to be easily and accurately adjusted with respect to the clamp. This operating 20 shaft 17 carries a miter 22 which meshes with a miter 23 on a stud 24, taking bearing in the walls 21 and 25 of the head. Fast on the stud 24 is a gear 26 located in the head, which gear operates a pinion 27 25 mounted on a stud 28 which takes bearing in a projection 29 depending from the head 14, the teeth of the pinion projecting from the head through a suitable opening in the projection. 30 With this construction the operative parts are protected, so that dirt and other foreign substances are not easily accessible to them, and the operator is protected from any moving parts. Furthermore, by the arrangement adopted, the gearing occupies a small space.

The means whereby the tool may be positively held in operative relation with the clamp may be somewhat varied. In the 40 best constructions, these means will be such that the tool may be locked to the clamp. As shown, the head is provided with a pair of projections or ears 30, one on each side of the head, in which are pivoted a 45 pair of locking latches 31 provided with locking jaws 32, these jaws being arranged to take under ribs or other suitable projections 33 formed in the ends of the clamp. These jaws are, furthermore, preferably 50 spring jaws, being held in locking relation with the clamp by means of springs 34, against which the jaws are rocked to release them from the clamp. With this construction the tool is positively held in 55 locked relation with the clamp, but may be easily manipulated to effect the clamp adjusting operation.

Tools embodying the invention in its best form will also be provided with means for assisting in positioning them in proper 60 relation to the operating gears or walls of the clamps. While these means may be varied, in the particular construction illustrated the wall 21 of the head is provided with one or more positioning pins 35, which 65 are arranged to enter a suitable hole or slot 36 formed in the edge of the clamp, these pins acting to position the tool in proper relation with the clamp gear or wheel. 70

While the invention has been shown and described in its preferred form, it will be understood that various changes may be made in the specific construction shown and described, without departing from the invention. 75

What is claimed is:—

1. In a plate clamp operating tool, the combination with an enclosed casing having a beveled side, of a driver mounted in the 80 casing, a shaft therefor, a handle for operating the shaft, driven gears mounted in the casing and operated from the driver, one of said gears co-operating with the adjusting mechanism of a plate clamp, and 85 a positioning device projecting from the beveled side of the casing for positioning the casing with respect to a clamp.
2. In a plate clamp operating tool, the combination with a tool body, of a pair of 90 locking jaws pivoted thereto, and springs for holding the locking jaws in positive locked relation with a plate clamp.
3. In a plate clamp operating tool, the combination with an enclosed casing, of 95 plate clamp adjusting devices mounted therein, and a pair of pivoted locking jaws mounted outside the casing for positively locking the casing in operative relation with the plate clamp.
4. In a plate clamp operating tool, the combination of an enclosed casing, operating gears mounted in the casing, one of 105 said gears co-operating with the adjusting mechanism of a plate clamp a handle for operating the gears, a positioning device for positioning the casing with respect to the clamp, and means for positively locking the tool body in operative relation with the clamp.

In testimony whereof, we have hereunto set our hands.

OSCAR ROESEN.
ISIDOR TORNBERG.
